UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

APPARATUS FOR DIRECTIVE SIGNALING.

Specification of Letters Patent. Patented Aug. 10, 1920.

1,348,856.

Application filed December 26, 1918. Serial No. 268,231.

To all whom it may concern:

Be it known that I, REGINALD A. FESSENDEN, of Brookline, in the county of Norfolk and State of Massachusetts, a citizen of the United States, have invented a new and useful Improvement in Apparatus for Directive Signaling, of which the following is a specification.

This application is a continuation of application Serial No. 186,627, filed August 16, 1917 so far as may relate to similar matter.

My invention relates to the transmission and receipt of energy and more particularly to signaling and still more particularly to directional signaling, especially the location of submarines and submarine signaling stations and also of aeroplanes.

The object of my invention is to improve the acoustic efficiency of the sending and receiving energy and more especially to improve the efficiency of signaling and still more to improve the efficiency of apparatus and methods for locating submarine signaling stations and submarines. It may be used on shipboard or otherwise.

Figure 1 accompanying this specification illustrates, partly diagrammatically, apparatus adapted for carrying out my invention.

Fig. 2 is a diagram described below.

In the figure 33 is a vessel, for example of the destroyer type, and 30, 31 and 32 are the compartments of the forepeak or oil tanks of the torpedo destroyer, though they may be fluid containers otherwise located, according to circumstances.

11 and 12 are sound receiving devices of any suitable kind; for example microphones or stethoscopes or electro-magnetic receivers and preferably oscillators of the kind described in United States Patent No. 1,167,366. I shall hereinafter refer to these, generally speaking, as sound detectors.

These oscillators are shown as located on board ship and are placed in any suitable position in reference to each other, either side by side, or, as shown, back to back in the same tank or adjacent fluid containing tanks, and preferably have their faces perpendicular to the skin of the ship. As shown, they are separated by the sound insulating screen 13, 14, of any kind, being attached to each other and to it by the bolts 15, 16, which may be insulated therefrom by soft rubber or lead in a known way.

Both oscillators and sound screen are

mounted on a pivot 29 and can be rotated by any suitable means, as for example by the handle 17.

The sound screen 13, 14 may be constructed and shaped in any suitable way to produce the desired result; for example at the end 14 the sound screen is shown in curved shape so as to shield to a greater extent than at the end 13.

I prefer so to shape the sound screen 13, 14 that a sound coming from a given angle and striking the oscillators will be heard with the same relative intensities and phases as a sound coming from the same angle and striking the head of a human being.

The shape of the sound screen to accomplish this is best determined by experiment, the shape being varied until a person listening in on telephone receivers attached to the oscillators will obtain the same change in relative sound intensities in the two receivers when the oscillators are turned to a certain angle as he obtains when he turns his head through the same angle.

An important point to note is that when the oscillators are used in a different medium from air, for example in water, the distance of the oscillators apart should preferably bear the same relation to the velocity of sound in such medium, for example water, as the usual distance apart of the two ears of a human body bears to the velocity of sound in air. For example, if the distance between the ears is 8 inches and the velocity of sound in air is 1100 feet per second, then if the oscillators are immersed in water, in which the velocity of sound is 4400 feet per second, the oscillators should preferably be placed a little less than 3 feet apart. If the oscillators are placed farther apart, as for example 10 inches, still further changes are obtained and the sound screen must be extended still farther in order to obtain the desired effect on turning the oscillators around on their pivot 29.

18, 19, 20, 21 are leads from the oscillators to the indicators shown as telephone receivers 26, 27, which with the other apparatus may be located upon the bridge or other convenient place and are connected by the head band 28, but are not electrically connected to each other.

33 and 34 are switches for opening or closing the lead circuits as desired.

22, 23 are adjustable capacities, and 24, 25

are adjustable inductances. These capacities and inductances have the function, in addition to their other functions, that by changing their relative values the phase of the sounds reaching the receivers 26, 27 can be altered without turning the oscillators on their pivot, or, if the oscillators are turned on their pivot, the change of phase may be increased or decreased.

10 For example, if a sound is received on the port bow, the oscillators may be either turned by means of the handle 17 until the sound appears to come from a point perpendicular to and in front of the line joining the centers of the diaphragms of the two oscillators, the sound then being equally loud to both ears of the observer, and the angle through which the handle 17 is being moved may be measured and the exact 15 direction of the sound may be thus determined. Or the oscillators may be left stationary and the condensers 22, 23, or inductances 24, 25, or both, adjusted until the sound appears dead ahead and the readings 20 of the condensers and inductances taken and in this way the exact direction determined. Or both oscillators and condensers and inductances may be left stationary and the vessel turned until the sound appears to 25 come in dead ahead and the bow is pointed in the direction of the source of sound.

The tanks 30, 31, 32 are preferably filled either with water or oil, and when the oil is used up, it is preferably replaced with 30 water.

It is to be noted that 30, 31 and 32, are the oil tanks or water tanks, and that the chamber between oil tank 30 and the bow of the vessel, and the chamber between oil 35 tank 32 and the stern of the vessel are not oil or water tank chambers, and being filled with air may be called air chambers, and as such do not conduct sound to anything like the same extent as if they were oil 40 tank chambers, and hence do not conduct sounds originating at the bow and stern of the vessel into the oil tanks 30, 31 and 32.

The insertion of the oscillators in fluid filled tanks, for example forepeak tanks, or, 45 as shown, in oil tanks, has the great advantage that, as applicant has discovered, it enables the sound to be received nearly as well dead ahead as abeam.

For example, with the installation placed 50 on the S. S. *Devereaux* the distance at which it was possible to send and receive dead ahead was 31½ miles as against 36 miles abeam. With the installation placed on the U. S. 55 destroyer *Aylwin* the working distance dead ahead was 84% of that abeam.

Fig. 2 illustrates diagrammatical tests made on an insulation of this general type, 60 representing the vessel, the dotted line 41 representing the range obtained at different angles with oscillators installed in

the skin of the ship and the full line 40 is corresponding range with the oscillator mounted in tank as shown above.

I have discovered that it is possible to still further increase the range dead ahead or dead astern by making the skin of the ship or the wall of the tanks or the chamber containing the sound receiver so that the index of refraction of the skin of the ship or the wall of the tanks relative to water is unity.

For example, the velocity of sound in water is approximately 4400 feet per second, while the velocity of sound in steel is approximately 17,000 feet per second. Consequently, sounds striking the skin of the ship at a small angle are totally reflected and do not enter the ship and affect the oscillators.

I have found, however, that by loading the skin of the ship so that the index of refraction of the skin of the ship or the wall of the tanks relative to water is unity not only are water noises greatly lessened but also sound passes directly from the signaling station to the oscillator, almost as if the skin of the ship were not there.

One method by which I accomplish this is to electrically weld, or otherwise suitably attach, lumps or disks or plates of lead or other suitable material, such as tungsten, to the inside of the skin of the ship, or to use material such as zinc or tin or tin alloyed with lead, or to use a plate having holes punched in it, the holes being filled with lead or brass. Other arrangements may suggest themselves, but whatever the arrangement used, it should be such as to make the index of refraction of the skin of the ship or the wall of the tanks relative to water equal to unity, and if weights are used, such as disks of lead, they should be close together, i. e., the distance between any two adjacent ones should be approximately equal to less than a quarter wave length of the sound which is to be received.

This method is also of value as a method of eliminating high pitched sounds which it is not desired to receive, as sounds whose quarter wave length is less than the distance between the weights may be refracted while sounds of longer wave length will be transmitted.

Other arrangements of apparatus to accomplish this result and be within the scope of my invention will occur to those skilled in the art.

What I claim as my invention is:

1. The combination of a ship, a liquid-containing chamber extending the full width of the ship, sound-insulating chambers located between said liquid-containing chamber and the bow and stern of the ship, and submarine-acoustic means located within the liquid in said chamber.

2. The combination of a ship, a liquid-containing chamber extending the full width of the ship, sound-insulating chambers located between said liquid-containing chamber and the bow and stern of the ship, and submarine-acoustic means located within said body of liquid.
3. The combination of a ship, a liquid-containing chamber located within said ship and extending the full width of the ship, sound-insulating chambers located between said liquid-containing chamber and the bow and stern of the ship, and submarine-acoustic means located within said liquid and on the longitudinal axis of the ship.
4. The combination of a ship, a liquid-containing chamber extending the full width of the ship, sound-insulating chambers located between said liquid-containing chamber and the bow and stern of the ship, and submarine-direction-finding means located within the liquid in said chamber.
5. The combination of a ship, a liquid-
- containing chamber extending the full width of the ship, sound-insulating chambers located between said liquid-containing chamber and the bow and submarine-direction-finding means located within said body of liquid.
6. The combination of a ship, a liquid-containing chamber located within said ship, sound-insulating chambers located between said liquid-containing chamber and the bow and stern of the ship and extending the full width of the ship, and submarine-direction-finding means located within said liquid and on the longitudinal axis of the ship.
7. The combination of a ship, a liquid-containing chamber extending the full width of the ship, sound-insulating chambers located between said liquid-containing chamber and the bow and stern of the ship, and two submarine-acoustic devices located within said liquid.

REGINALD A. FESSENDEN.
